UNITED STATES PATENT OFFICE

GEORGE HOLT FRASER, OF BROOKLYN, NEW YORK

SEPARATOR

Application filed April 27, 1925, Serial No. 28,033. Renewed July 9, 1930.

This invention relates to air separators or dust collectors for separating and collecting fine material, and aims to provide improvements in such for use with mills of the 5 ring and roll or other type and for air separators used in connection therewith or otherwise, and to provide an improved pulverizing and separating machine.

Heretofore a plurality of planetary rolls 10 have been revolved about the interior of a crushing die to pulverize material between the peripheral crushing faces of the rolls and the inner crushing face of the die. Centrifugal force incident to the speed of the planetary 15 travel of the rolls has been used as the crushing force. Air has been circulated in below the ring and up through the crushing zone to float out the fine material to permit its separation and to return the air in an endless circuit through the mill and separator. Revolving plows in front of the rolls have lifted fallen uncrushed material up to the crushing zone. A chamber above the crushing 20 elements has permitted coarse particles to fall as the fine particles have gone through a sinuous passage around a deflector and depending lip to the air outlet. A fan connected at its suction side to the air outlet and at its blast side to piping communicating with 25 a remote dust collector has been used to withdraw and convey the fine material to its destination. A return pipe for the cleaned air is connected between the exhaust of the dust collector and a tangential return chamber 30 surrounding tangential air inlets beneath the crushing zone of the mill to return the air with a whirling effect below and inwardly of the ring.

Heretofore, in return current pulverizing 35 and separating machines enclosed in an outer casing affording an annular passage for the separating current, for example, as shown in my Patent No. 1,499,516, dated July 1, 1924, such casing has enclosed as part of the current path a dust chamber below the crushing chamber and through which the separating current has flowed under the open bottom wall of the crushing chamber to return through an opening under such wall, and there has been no closed uncrushed material

retaining communication preventing wall spaced below the crushing chamber and below the path of the separating current and above the dust chamber for preventing communication between the uncrushed material 55 and the dust chamber or between the separating current and the dust settling in the dust chamber, affording above such wall an inward passage for the separating current and around said wall a currentless dust passage to the dust chamber.

My invention aims to provide improvements especially applicable to air separators for use with mills operating on this principle, and in pulverizers for use with return current air separators, and to provide an improved combined mill and air separator for pulverizing and separating material by this method.

To this end in carrying out the preferred 70 form of my invention I provide an improved air separator preferably having between its material dropping opening and its dust chamber means for retaining and sustaining unseparated material below the separating current, and means for tossing such sustained material into such path, and an outer casing 75 preferably enclosing or enveloping the crushing chamber and crushing elements and exposing the main frame and driving mechanism, and I provide an inward current passage above such retaining means, and currentless downward dust passing means around said retaining means, preferably as 80 ducts communicating between the return air chamber of the separator and the space below the crushing chamber for returning air beneath the latter without passing the air through the dust chamber, and I provide 85 a closed communication preventing material sustaining wall spaced below the crushing chamber and above the dust chamber and affording a bottom wall for the inward current passage for the returning current above such wall, and around it currentless downward 90 dust passages to said chamber, preferably as fine ways or conduits for conducting fines out of and below or across the zone of the returning air and past and without the crushing 95 and driving elements to beneath the lat- 100

ter, and I provide improved means for filtering or cleaning dust laden air, and a variable separating or settling chamber and adjustable bellows like transverse cross chamber wall above the crushing chamber for varying the fineness of the outflowing dust, and an adjustable damper for varying the air outlet, with the aim of effecting pulverization in the crushing chamber, selection and fineness of dust above it, separation of the dust immediately around it, unmolested collection of the dust below and out of the zone of the returning current and return of the air below the crushing chamber and above the dust chamber.

And I also provide a pulverizing chamber having an upper outlet for pulverized material and an open unpulverized material dropping opening within and in spaced relation to an outer casing and affording up through and down around said chamber and in under its crushing elements an endless current passage, and a dust collecting chamber below said chamber, with a communication preventing uncrushed material receiving bottom wall spaced below said dropping opening and affording below said crushing elements and above said bottom wall an inward return current passage, and affording around said wall a currentless downward passage for such dust, and affording below said return current inlet and above said dust chamber a communication preventing wall for preventing communication between said coarse material and said dust chamber, and I preferably dispose said wall under and encircled by said cleaning means, and I preferably provide current means revolving concentric of and above said dropping opening for circulating a separating current up through and down around and in under said crushing chamber and above said dust chamber in the form of a vortex ring, and I preferably provide material uptossing means below such current means and above said wall and encircled by said cleaning means for uptossing such material in the up-leg of such vortex ring of cleaned returning current and into the path of said crushing elements, and I preferably provide said crushing chamber with a variable cross chamber partition affording a variable selecting chamber below said outlet for varying the area of the up-leg of such vortex ring and varying the fineness of dust floating from said crushing chamber.

And I also preferably provide two co-operating crushing faces, the upper one the usual concave or cylindrical upwardly extending die face against which the material is crushed by impact and pressure and the lower one a contiguous nearly flat but preferably slightly downwardly and inwardly tapering annular attrition face or shelf on which the primarily crushed material from above may be frictionally further reduced,

similar reciprocal faces being preferably provided on the one or more centrifugal crushing rolls cooperating with these.

And I also preferably provide a revolving feed disc mounted to move with a diaphragm 70 operated by variations in air pressure below the crushing chamber to vary feed according to such variations, and a stationary feed pipe concentric of and opposite this disc, and a regulating feed collar around this pipe and 75 mounted on a diaphragm balanced to move with variations in the suction at the egress part of the fine chamber to vary feed with such variations.

And I preferably provide an axially adjustable feeding screw conveyor for impelling more or less feed from the feed hopper to the feed pipe, and an inclined and preferably pivotally adjustable discharge edge beneath one length of conveyor flight thereof 85 to graduate the discharge from the conveyor into the feed pipe to approximate a uniform stream instead of an intermittent dropping.

And I provide various other features of improvement in the construction, arrangement and operation, all of which will be hereinafter more fully set forth with reference to the accompanying drawings, in which

Fig. 1 is a side elevation, partly in vertical axial section, of the preferred form of my improved pulverizer and separator;

Fig. 2 is a plan view thereof partly in horizontal section on the planes of the lines 2—2 in Fig. 1;

Fig. 3 is a horizontal section thereof on the planes of the lines in Fig. 1;

Fig. 4 is a small side elevation thereof as arranged for elevating or conveying the dust laden air to a remote point for separation by my improved dust collector, the parts being broken out to show them partly in section on the planes of the lines 4—4 in Fig. 5;

Fig. 5 is a similar plan view thereof partly in horizontal section on the planes of the lines 5—5 in Fig. 4;

Fig. 6 is an enlarged axial section of the roll;

Fig. 7 is a vertical section showing my improvements as applied to a revolving ring roll mill having my improved spiral case, and 115 direct outward acting springs, and reversely acting stop chatter springs;

Fig. 8 is a plan view thereof partly in section; and

Fig. 9 is a vertical axial section of my improved air separator alone.

Referring to Figs. 1 and 2 of the drawings let A indicate the ring, B the rolls, C the main frame or casing, D the drive, E the feed entrance, and F the fine outlet, of a pulverizing separating machine.

These parts may be of any usual or suitable construction affording a crushing chamber and crushing elements therein which can cooperate to pulverize coarse infed material 130

and separate and withdraw pulverulent material. Either or both of the crushing elements may revolve about a vertical or other axis, and centrifugal force or other means may be used for generating the crushing force necessary to pulverize the material between the reciprocal coacting crushing faces of these elements.

As shown the ring A is an annular die mounted in the frame or base C and having a vertical cylindrical inner crushing face disposed about a vertical axis, and the rolls B revolve in a horizontal plane about this axis and each has a vertical cylindrical peripheral crushing face running against and coacting with the crushing face of the ring to crush material between these faces. A plurality of planetary rolls is preferably used, four being shown, and each being movable radially of the ring and free to revolve on its own axis as it tracks on the inner face of the ring. Impelling plows or agitators G revolve with the rolls to raise and throw the material to be crushed up in front of them and on to the face of the ring in advance of the bight of the rolls. A revolving head or carrier H sustains and propels the rolls and plows around in a crushing chamber I. The crushed material passes from the crushing chamber into a settling or precipitation chamber J from which pieces are returned to the crushing chamber and finer pieces passed to a selecting chamber K from which the oversize is likewise returned and the fineness desired passes through the dust outlet L. Air is usually used to withdraw the dust from the crushing chamber and is circulated by a suitable blower as the fan M through an endless circuit N comprising a dust collector for separating the dust and a return passage for returning the air within the crushing chamber with which it communicates through a plurality of tangential air inlets or ducts O at the side of this chamber remote from the chamber J. this endless circuit comprising all said chambers and the blower chamber and the dust collector or separator and such communicating or external passages as are desirable or necessary to connect and include these to permit depositing the dust where desired and continually reusing the air.

My invention provides various improvements in devices of this character, and I will now describe these in detail in their preferred form, referring particularly to Figs. 1 and 2 of the drawings.

According to one feature of improvement each roll B is mounted to revolve on and swing with a movable revolving tension impeller P pivotally and preferably movably and adjustably mounted on the carrier H to revolve therewith and drag the roll around within the ring. As shown the impeller P has an upwardly projecting pin a revolvably

carrying the roll, a horizontally extending body b beneath the roll and a downwardly projecting pin c swingingly connecting it to the carrier on which it is yieldingly sustained by a spring d adjustable to vary its height and resiliently resisting while yieldingly permitting its upward movement and acting to elastically depress it to generate a downward crushing force for the roll when this is desired. The impeller P normally swings on an axis parallel with the axis of the carrier H, but preferably it can be adjusted out of parallel with this axis to give a slight inclination to the axis of rotation of the roll as it revolves against the inner face of the ring to cause it to tend to run downwardly on this face and thus to effect a slight friction or attrition between these faces to supplement its direct crushing action. This is preferably accomplished as shown in Fig. 1 by mounting the pin c in an adjustable or pivoted bushing e by tilting which the pin may be thrown out of parallel with the axis of the carrier H. The roll B is preferably movable and removable on the impeller P and preferably yieldingly held thereon and subject to variable resistance or retardation in its movement thereto and in its revolution thereabout. Preferably the roll is bored to reversibly fit on and interlock with the exterior of a bushing f having lugs g which pass through grooves h in the roll and enter recesses i therein to lock the two together, and the bushing f runs on the pin a upon which it is axially movable against the tension of a spring j adjustable against a key washer k by a nut l to vary the tension of the spring and when desired to give a brake effect tending to resist revolution of the roll and increase its drag or attrition on the ring. The bore of the roll is sufficient to clear the washer so that by turning the roll back on the bushing until its grooves h coincide with the lugs g the roll can be lifted off for renewal or reversal without disturbing the other parts.

According to another feature of improvement my invention provides an annular grinding shelf, ledge, face, or surface, which is preferably a separate ring of relatively non-wearing material Q, auxiliary to and at the lower side of the grinding ring A and projecting inwardly therefrom opposite and partially across the end of each roll B, which I preferably form or provide with a reciprocal supplementary and removable end grinding face R opposite and coacting with the face Q to grind material between them with a roll and attrition action dependent on the adjustment of the roll toward the shelf or the weight of the roll or the spring tension applied to it. The faces Q and R are more or less flat to suit the particular work required of them, but are preferably similarly inclined curved or coned to vary their prox-

imity as the roll moves inwardly and outwardly. As shown the face Q is the conical upper surface of a horizontal ring which is seated in the bottom of the socket for the ring A and held in position thereby, and the inner edge of which projects inwardly under the rolls and forms the top of the air inlets O, and the plows G clear this edge to throw any fallen material back up on to the shelf. As shown the crushing face R on the roll instead of being formed integral therewith is formed as a separate conical ring removably coupled to the end of the roll by lugs *m* reciprocal to and interlocking in sockets in the roll to connect these parts and cause them to rotate and revolve together. The sockets *n* are duplicated at each end of the roll so that it can be reversed and interlocked with the end grinding ring R in either position, and serve as convenient means for lifting it when removing the roll by raising it off the arm P, the bore of the ring R being sufficient to clear the lugs on the bushing *f*.

By this means when the attrition faces Q and R are not used alone for attrition grinding they supplement the grinding action between the rolls B and the ring A by receiving material initially crushed by and falling from them and frictionally further grinding it as it passes between the end of the roll and the face Q from which it may fall into the incoming air current for floating out the fines and on to the plows for elevating the coarse for further grinding.

The face Q may be formed integrally with the ring A and the face R may be integral with its roll B, but to provide for difference in wear effect, and for varying the several crushing faces to suit different materials or requirements I prefer to segregate these faces by forming them on separable and independently removable members.

The roll may move axially as its face R rides up the face Q to surmount material on the latter, and in such case exerts an axial attrition effect on the ring Q in addition to its impactive and centrifugal crushing actions.

According to another feature of improvement I provide a casing S above the crushing chamber which preferably has an upwardly and outwardly flaring lower portion *o*, a cylindrical portion *p* thereabove and a flat top *q* and serves as the outer wall for the precipitation chamber J, and I preferably provide an adjustable partition T within and sub-dividing the interior of this casing into the precipitation chamber J and the selecting chamber K, which partition preferably has the form of a movable annular wall inclined similarly to and movable towards and from the wall *o* and acts as a bellows or damper to vary the volumetric area of the chambers J and K and the space above its upper edge through which air is permitted to flow from the former to the latter to vary the speed of

the air current in these chambers and to correspondingly vary the fineness of the material which shall be floated from the chamber J into the chamber K. When the partition T is adjusted toward the wall *o* current speed is increased and larger particles will be carried over the upper edge of the partition and into the chamber K, from which those fine enough to float out the outlet L will pass and those too coarse will fall and return to the crushing chamber around the lower edge of the partition T.

My invention provides an adjustable damper U around and under the outlet L preferably as a ring around the depending pipe affording an outlet L, by vertically adjusting which damper the height of this outlet relatively to the partition T can be varied and this damper and the partition are preferably simultaneously oppositely adjusted by three or more tilting levers *r* operated from without by the forked ends of a rod *s* so as to uniformly operate the parts from three equidistant suspension points.

The suction pipe of any blower may be connected to the outlet L for exhausting the dust and conducting it where desired, and any dust collector may be used there for extracting the dust, and any return pipe may lead from its exhaust to the air inlets for returning and using the air, but according to the preferred form of my invention I provide the blower M above and concentric to the pulverizing chamber and within the casing enclosing it, which preferably consists of blades driven synchronously with the carrier H, and preferably at the same speed as by being detachably mounted on pipes *t* carried thereby. The top *q* of the inner casings serves as a lower shelf for this blower, and the top wall *u* of the outer casing V serves as the top wall for the way for these blades, the outer ends of which are preferably terminating near the inner inclined edge of the beveled deflector Y or corner of the casing V to deflect out-blown air downwardly into the passage N. The casing V preferably is mounted on the main frame C and encloses the upper part thereof as well as the crushing, precipitation, selecting, blower, separator, and return chambers, but exposes the lower part thereof for access and adjustment. It preferably has a vertical cylindrical outer wall *v*, and an inner conical deflecting ring *w* parallel with and opposite the wall *o*, which ring deflects the air inwardly and terminates sufficiently above the top of the frame C to afford a suitable outward air passage above the latter through which the returning air may flow outwardly around the upper edge of the frame C and then downwardly to the return openings O, to which it is guided by the inwardly inclined bottom wall *x* of the casing V.

According to another feature of my in-

vention I preferably provide filtering means W for intercepting and conducting out of the zone of the current particles floating therein to clean the air before it is returned to the 5 crushing chamber, and I preferably dispose these in the passage N at the point where the air passes outwardly immediately over the top of the frame C . These preferably consist of a plurality of rows of hollow baffles 10 or troughs extending vertically from the wall w with their inner hollow faces opposed to the outwardly flowing current, those of one row being staggered relatively to those of the next, to form current voids in which floating 15 particles may precipitate while affording spaces between their edges for passage of the returning current. The lower ends of these preferably enter a wall y which is preferably conical and downwardly and inwardly inclined and spaced from the wall x and affords a downward and inward way for the 20 separated dust as well as an inward wall for the return passage N . Any means for extracting the dust may be used but my invention 25 preferably provides foraminous means surrounding and concentric with the crushing elements and the returning air passage to afford an outward passage for the air current and a downward or inward passage for 30 the dust, and for bringing the separated dust inwardly of the returning air above the latter as returned to the crushing chamber.

According to another feature of improvement my invention provides separate non- 35 communicating dust and returning air passages, preferably as alternate ways for the separated dust and the return air to conduct the dust below, past, or across the returning air and below its zone and to conduct the air 40 past the dust and above the dust passage and above the dust chamber and into the crushing chamber. Preferably I provide downwardly and inwardly and tangentially disposed dust passages X intermediate of and similarly disposed to the air passages O , which are 45 shown as tubular ways against or through the tangential webs of the frame C which separate and passages O and connect the upper and lower parts to the frame. Thus the lower 50 ends of the dust ducts X are substantially inwardly of the outer ends and within a diameter approximately corresponding with that of the main ring A , and the dust can be safely conducted downwardly and inwardly 55 through the returning air zone without molestation and without interfering with exposure of and access to the bottom flange of the main frame.

According to another feature of improvement 60 the driving mechanism is preferably enclosed within the dust passage and above the dust chamber by non-communicating wall means, and preferably is carried by the annular bottom frame or casing Y which is 65 movably adjusted to the frame C , and ac-

cording to my invention is preferably provided with a plurality of downwardly and inwardly extending dust ducts z disposed radially under and respectively an extension of the corresponding duct X in the frame C to 70 conduct the dust below and past the driving mechanism and inwardly toward the axial center of the machine, which ducts at their lower ends open into and are enclosed by a dust cone Z removably adjusted to the bottom of the frame Y and terminating at its 75 lower end in the central dust spout F .

The ducts X and z preferably are tubular and respectively afford between them spaces or passages affording inward access to the interior, as the air spaces O through the frame C , and the openings a' through the frame Y . The bottom of the frame Y is preferably open and according to one feature of my invention I prefer to removably attach to or suspend from it a hollow or cup shaped frame A' affording a non-communicating wall depending within and spaced from the dust cone Z to utilize the space in the upper part of this while affording around the frame an 80 annular passage for the dust to descend in the cone and at the same time isolate the gear chamber B' from the dust. The solid bottom c' of the base frame C affords a closed bottom wall spaced below the crushing 85 chamber and a non-communicating wall above the dust chamber and closes the top of the gear chamber and carries a removable and renewable pan or bottom b' of wear resisting material which affords a closed material retaining sustaining bottom wall for the inward current passage above it and affords around its outer edge a space for the dust passages X , and affords a bottom for the crushing chamber and protects the top wall 90 c' of the frame Y , which latter extends inwardly and has a central bearing hub through which the vertical shaft d' runs, the lower end of the shaft being adjustably supported on a ball bearing e' . The carrier 95 H is removably keyed to the shaft d' to revolve with it, and it supports and is driven by a driving hub C' keyed to it within the driving chamber.

According to one feature of my invention 115 the driving hub is preferably provided with a removable bevel gear D' meshing with a bevel pinion E' on a shaft f' mounted in a bearing g' between two ducts z and extending outwardly to a pulley H' by which the 120 mill may be driven, and is also preferably with a removable pulley flange F' by which it may be driven by a horizontal belt passing through any two of the openings a' if direct belt drive is preferred, and is also preferably 125 provided with a removable gear G' meshing with a pinion i' on a reducing gear j' running in a stationary arm k' and meshing with a gear l' on the rotor of a motor H' which according to my invention is prefer- 130

ably mounted in the hollow frame A' to afford a direct motor drive with suitable speed reducing and compensating couplings, and switches and electrical connections, all of which may be removably mounted in the hollow lower frame and suitably connected through the openings a' of the gear frame. In this manner the device may be driven in whichever of several ways is best suited to local conditions.

According to another feature of my improvement the carrier H is preferably provided with a hollow portion or cylindrical extension m' affording an expansion chamber I' in communication with and below the crushing chamber and subject to variations of air pressure below the latter, and the top of the chamber is closed by a diaphragm J' which preferably utilizes variations in this pressure to vary or regulate speed of feed of material to the chamber, in any suitable manner, but preferably by mounting on it the revolving distributing disc K' which receives the feed and projects it radially over the top of the rolls toward the crushing ring.

A central vertical adjustable feed pipe L' preferably opens at its lower end opposite the center of the disc K' and spaced sufficiently from it to permit the maximum inflow of feed desired. Increase of air pressure below the crushing chamber due to abnormal accumulation of uncrushed material there will cause an upward pressure against the diaphragm and this will deflect it upwardly to raise the feed disc closer to the end of the feed pipe and correspondingly diminish inflow of fresh feed, and the disc will be thus vertically moved automatically to regulate and vary the feed to accord with the speed of withdrawal of fines from the chamber.

The feed pipe is preferably suspended from a hopper M' by a pin n' adjustable in a spirally stepped notch or slot o' in the neck of the hopper so that by turning and setting the pipe its vertical position can be adjusted.

My invention preferably also provides for further adjusting and for automatically regulating or varying the speed of feed by an annular ring N' surrounding the lower end of the pipe and suspended by rods p' adjustably carried by nuts q' which I preferably sustain by an annular diaphragm O' mounted on the top u and movably surrounding the feed pipe and subject to variations in air pressure adjacent to the intake side of the fan M, so that as the suction is increased due to overloading the crushing chamber the diaphragm O' will be deflected downwardly and lower the ring N and correspondingly vary the speed of feed with variations in the suction. Preferably I provide an adjustable weighted forked lever P' for sustaining the diaphragm O' and regulating its movement.

Thus the feed may be mechanically varied or regulated and may also be automatically pneumatically varied or regulated by over pressure below or abnormal suction above the feeding chamber or by either.

My invention preferably provides for mechanically measuring and regulating the supply of feed and for equalizing its discharge to the pulverizer, and this I preferably accomplish by utilizing an axially adjustable spiral screw conveyor Q' revolving in a trough R' and having an angular outlet discharge edge r' over the trough, which edge is preferably adjustable around the conveyor and transversely of its axis to vary its position and angularity to cause the cone of material progressing in front of each conveyor flight to gradually dribble over the edge and thus uniformly discharge itself into the hopper. The edge is preferably the length of the pitch of the conveyor to extend from the edge of one to the next flight, and may be adjustable by revolving the trough which is preferably pivoted to two independently revoluble bands s' surrounding the trough and which may be adjusted on it to vary the position and angularity of the edge, the trough being cut with a large enough hole at its under side to permit discharge in any position of the edge. The edge is preferably reversely duplicated at the other side of the flexible angular sheet t' on which it is formed, so that it may be used with a right hand conveyor or a left hand conveyor by shifting its position to suit the hand of the conveyor used.

To regulate the amount of material moved by the conveyor its intake end is preferably axially adjustable toward the hopper S' so that it will take up more or less material according to its adjustment toward the hopper where its end engages the entering material as its angle of flow permits it to run into the trough. The hopper S' is preferably inclined and rotatable so that its inlet u' may receive an angular or vertical pipe or chute. The outer end of the conveyor shaft is screw threaded to receive a hand wheel v' for adjusting it, and its inner end plays in the elongated socket of the head w' of the trough, which is screw threaded and carries a screw x' for adjusting this end of the shaft. Speed of revolution of the conveyor is varied by oppositely inclined cone pulleys T' one of which is driven by a belt y' from the shaft f' and drives the other through the adjustable friction belt pulley or ring z'.

My invention preferably provides for beating, agitating and disintegrating the infed material, for which I preferably provide one or more annular hollow shelves or troughs U' around the distributing disc K' for receiving material thrown from it, which troughs are non-rotatably supported from the casting S and receive revolving stirrers, beaters

or agitators V' which plow through the material accumulating in the troughs and agitate and beat it and toss it upwardly and outwardly into the uprising air current at the sides of the troughs so that it can fall past the edges of the troughs and through this current to permit the current to float upwardly fine material and let the grit or larger pieces descend into the crushing chamber to be carried or fall through it to the bottom or grit pan b'. The troughs U' sustain lumps of balled material and the stirrers disintegrate these before throwing them into the air current, to pulverize such lumps and adapt their dust for separation by the rising current.

According to another feature of my invention the pan b' receives all pieces falling through the chamber, and inclined plows or scrapers W' push such material outwardly on the pan and into the path of the lifting plows G which toss it upwardly across the path of the incoming current through the air inlets O so that this current can catch and blow inwardly and upwardly any fine dust falling into the pan. The plows G have curved upwardly outer flanges to prevent the material being thrown centrifugally outward, and above them I preferably provide inclined deflectors X' against which upwardly projected large particles may impinge and be deflected outwardly across and out of the zone of the rising current, and may fall onto the annular grinding faces.

In operation, speed of supply of material to be pulverized will be regulated by the position and speed of the feeding conveyor, the intermittent charges propelled by its flights being equalized in their discharge to the feed pipe by adjustment of the inclined edge r'. Normal speed of feed will be determined by adjustment of the feed pipe L toward the distributing disc K, or by adjustment of the regulating ring valve N', and will continue except as varied by the automatic pressure operated feed varying means J' and O' or either of them.

Infed material will be projected across the rising air current which may extract dust from it, the remaining material falling onto the ring A to be crushed against its inner face by the outer faces of the rolls B, after which it will fall onto the shelf Q and be rubbed by the attrition face R of the rolls which push it off the ledge and into the rising air current through which the coarse will fall onto the pan b' and by which the dust will be floated up through the crushing chamber. The plows G will scrape off the particles falling onto the pan and throw them upwardly in front of the roll where they will again be subjected to these crushing and rubbing elements and any dust released by this agitation will be floated up by the rising air current, which will carry

all dust into the settling chamber J where large particles may fall back into the crushing chamber while fine particles float upwardly.

The bellows partition T will be adjusted vertically to vary the area of the current passage in the chamber J to vary the speed of the current therethrough to determine the fineness of dust which it shall float over into the selecting chamber K, where the current will descend around the lower edge of the pipe L and pass up to the blower. In making this curve it will throw down larger particles and the size of these will be regulated by varying the outlet damper U.

If an outside blower is used it may be connected directly to the pipe L, and its speed will correspond to that required for withdrawing the dust desired and for conveying it to such remote point as desired, at which an ordinary cyclone dust collector will be located to extract the dust, and a return pipe will communicate between its relief outlet and the air inlets O, which will be enclosed by a spiral air chamber affording the lower end of such return pipe, as indicated in dotted lines in Figs. 1 and 2, but when these functions are to be effected in one machine the casing V will be adjusted to the base frame C to envelope its upper part and the fan M will be used to withdraw the dust laden air from the pipe L and send it through the passage N to the air inlets O, and the dust passages X will be used to conduct the dust below or through the return air, which will be cleaned by separating the dust from it as it returns, and the dust will be conducted past the drive gears to the dust chamber and discharge below and centrally of the machine.

Access to the dust chamber may be had by releasing and lifting the lower inclined wall x of the casing V, which wall is preferably detachable and telescopically engages the cylindrical wall v to permit this. Access to the driving chamber will be had between the ducts z. The gear case will be independently suspended from the frame C so that this case can be lowered to permit renewal of driving parts without dismantling the superstructure. The bottom c' can then be lowered for access to or downward removal of the pan b', carrier H, rolls B, pushers P, feed disc and plows, which can then be replaced from below.

It will be seen that my invention provides improvements which can be readily and advantageously availed of, and it will be understood that the invention is not limited to the particular details of construction, arrangement, or combination of parts, set forth as constituting its preferred form, since my improvements can be used in whole or in part, and according to any suitable or desired modifications, as the judgment of those

skilled in the art may dictate, without departing from the spirit of the invention.

When used in a mill of the type in which the ring is disposed about a horizontal axis 5 and is revolved by or revolves around rolls carried by movable non-rotative members my invention provides for using slightly concave and convex peripheral crushing faces on the ring A^2 and rolls B^2 and tapering attrition faces Q^2 and R^2 at each side of them, and for making the tapering faces on each side of the rolls yieldingly expansively act axially, by springs j^2 and bolts l^2 , within adjustably determinable limits relatively to the reciprocal faces on the ring and in such use my invention provides for placing my bellows T^2 in the precipitating chamber J^2 above the ring and using my filter W^2 for cleaning the air returning to the casing, 20 the dust passage X^2 extending downwardly between the returning air passages O^2 to conduct the dust below and without the crushing chamber and through and below the zone of the air current.

25 Where the upper driving roll and two lower rolls are used in such a construction I preferably mount the driving roll on the axis parallel with that of the ring and mount the lower rolls on reversely inclined axes 30 each having a slight angularity or wind relatively to the axis of the upper roll so that one roll tends to drive the ring slightly to one side and the other tends to drive it to a slight extent to the other side, thus balancing 35 their side driving action, and affording a slight friction or attrition effect between their grinding faces and those of the ring. This I preferably accomplish by providing all bearings in parallel and effecting wind of 40 the shafts by using eccentrically inclined bearing metal bushings between the shafts and their bearings, and differently faced thrust washers or thimbles in the end of the bearings to compensate for the resulting difference 45 in the angularity between the shafts and the other parts.

When a remote dust collector is used my invention provides for more completely extracting the dust from the air coming from 50 the pulverizer and blasted tangentially into the dust collector by providing an upper interior of the dust collector with a cylindrical portion a^2 in which the air may circulate to throw the coarse particles to the periphery 55 centrifugally, and by providing below this a corrugated metal lining b^2 in the corrugations of which this dust may descend past and below the zone of the current, and opposite the inner side of each corrugation I provide a hollow 60 vertical trough c^2 preferably semi-circular with its concave face opposed to the direction of revolution of the current so that the current may form dead spaces or current voids in front of these concave faces opposed 65 to its direction of whirl in which dust may

settle and be conducted through and below the zone of the current, the outer edges of which are in spaced relation to said corrugations to permit the current to divide and pass partly outside and partly inside of each hollow to avoid any tendency to circulate through and around the trough instead of forming air cones directly in front of them, and to equalize this circulation I preferably provide corrugated strips d^2 opposite and reversely shaped to the inwardly projecting ribs of the corrugated lining, spaced from this and from the inner edge of the troughs to afford uniform and similar passages at each side of the troughs and spaced from each other sufficiently to permit air inlet passages for the whirling air inwardly of them, so that as the air current whirls and descends it will be continually shaved off by these strips and directed toward the hollow faces of these troughs, and I provide a guard cone e^2 within the lower ends of these troughs to protect their discharge from molestation by the descending current, and above this an inner cylindrical wall f^2 affording around its lower edge an outlet through which current can pass inwardly and upwardly between vanes for checking its whirl, and another wall g^2 over which it can descend to pass through a double row of staggered filter 95 troughs or baffles h^2 to reach the central relief outlet i^2 for return of the cleaned air.

For remote conveying of the dust the current generated by the fan M alone or supplemental to that of an outside blower k^2 my invention preferably provides for removing and reversing and changing the current deflecting wall Y' from its normal position around the fan for blowing the current downwardly into the passage N to a reverse position in which one end is perpendicular and it is gradually twisted or adjusted in inclination in its extension around the fan so as to give a spiral effect similar to the inner wall of a blower affording a space around the fan gradually increasing to the other end and there discharging into a pipe leading to the suction of an auxiliary blower if used or direct to a remote dust collector Z' at a point where the dust is to be discharged. The inclination of the wall Y' when thus reversed should not exceed that at which any dust settling on it will slide down again into the path of the fan, which will throw it again into the current, and thus prevent clogging of this spiral path for the outblowing current. In such case the top of the passage N will be closed with a suitable cover and the relief pipe from the remote dust collector Z' will return to and enter this passage tangentially, so that the returning current will pass through the filter W for cleaning it of any dust remaining in it and thence through the air inlets O to the crushing chamber.

When applied to a vertical die mill the

revolving fan blades M^2 are mounted eccentrically of the casing, as by being mounted on the periphery of a revolving die A^2 so that the inner periphery of the casing C^2 affords an increasing space similar to the spiral interior of the blower casing to facilitate progress and discharge of the air current which is discharged upwardly at the point of greater area and floats the dust with it into the settling chamber where the grit is precipitated back into the crushing chamber and finer dust is carried over the adjustable partition T^2 into the selecting chamber J^2 , where oversize is precipitated and the fineness desired escapes with the air through the central outlet into the outer separating chamber where it passes through the filter to intercept the dust and send it to the dust outlet while permitting the cleaned air to return to each side of the crushing chamber near the point where the path of the fan blades is narrowest. In such case the grit is returned by gravity to the crushing elements.

When my improvements are used with an air separator alone as shown in Fig. 9 my invention provides a revolving adjustable horizontal partition m^2 within and for vertically varying the separating chamber and its upper outlet, and carried with a circular outlet varying valve or vertical partition n^2 on the blower M which are simultaneously adjustable to vary the area of the outlet passage above my adjustable bellows T , and it provides a baffle ring o^2 around the distributing disc p^2 for intercepting and dropping the pulverulent material, and a revolving cylindrical baffle q^2 on this disc, and revolving inclined flanged plows r^2 on this baffle under and for receiving material dropping from the ring for tossing it upwardly to agitate it in the rising air current.

In this construction my invention also provides a stationary pan s^2 under the feed disc and below the air current returning inwardly through the filter W^3 , for receiving fallen material, and a plurality of revolving inclined scoops t^2 for tossing this material upwardly in the path of the inward current to permit it to float the fine particles upward and throw coarser particles against the inclined wall u^2 to be deflected thereby outwardly into the tailings screen v^2 in the tailings cone w^2 . The scoops t^2 and stirring pushers x^2 are mounted on spokes sustained by and revolving with the disc p^2 , and act to toss up the material in the path of the incoming current in an air separator in the same manner as the plows G act in the construction shown in Fig. 1.

10. What I claim is:

1. In a separator, in combination, means affording a chamber for receiving pulverulent material, supply means for supplying such material to said chamber, blower means for causing a fluid current to flow up

through said chamber for floating fine material from said chamber, means above said chamber affording an outlet for such current, and adjustable wall means in said chamber comprising a vertically adjustable transverse wall below and across said outlet and substantially across said chamber and affording around the outer edge of said wall a space through which such current may flow from said chamber to said outlet and affording beneath said wall a variable passage for such current and adjustable to vary the area of such passage to vary the speed of flow of such current therethrough to vary the fineness of such material floated thereby. 70

2. In combination, means affording a chamber for receiving pulverulent material, supply means for supplying such material to said chamber, blower means for causing a fluid current to rise from said chamber to 80 float fine material therefrom, wall means comprising an annular outwardly flaring wall above and around said chamber and affording a separating chamber for receiving such current, and adjustable means within said separating chamber comprising an adjustable annular conical wall opposite and spaced from said wall and adjustable to vary the space between said walls to vary the upward passage for such current to vary the 95 fineness of material floated by it through such passage.

3. In combination, means affording a chamber for receiving pulverulent material to be separated, supply means for supplying 100 material to said chamber, blower means for causing a fluid current to flow up through and around and return beneath said chamber, outer wall means above said chamber affording an upwardly and outwardly flaring separating chamber communicating with said chamber for receiving such current, adjustable wall means within said separating chamber spaced from said flaring wall and affording an upper wall for varying the 110 volumetric area of the passage through said separating chamber to vary the speed of flow of such current therethrough, means above said adjustable wall affording a current outlet from said separating chamber, 115 and adjustable valve means for varying the space through which such current is permitted to flow.

4. In a separator, in combination, a casing enclosing a chamber, a receptacle within 120 said casing and having upper and lower openings communicating therewith, supply means for supplying pulverulent material to be separated within said receptacle, blower means for causing a fluid current to flow up through said receptacle and upper opening into said chamber and to return through said lower opening, and adjustable wall means within said receptacle opposite and across and spaced below said upper opening

affording a vertically adjustable transverse wall extending substantially across said chamber and affording above said wall a variable space through which such current is permitted to flow to said upper opening and vertically adjustable for varying the space through which such current is permitted to flow.

5. In a separator, in combination, means affording a chamber, supply means for supplying pulverulent material to said chamber, receiving shelf means for sustaining such material below said chamber, means affording a current passage below and to said chamber and above said receiving means, blower means for causing a fluid current to flow in said passage and up into said chamber, revolving plows above said receiving means and for tossing such material upwardly in the path of such current to subject fine material to the action of such current, and adjustable valve means for varying the speed of such current to vary the fineness of such material floated thereby.

25. 6. In a separator, in combination, means affording an upward chamber, supply means for supplying pulverulent material thereto, shelf means for receiving and sustaining such material, means below said chamber and above said receiving means affording an inward current passage communicating with said chamber above said receiving means, blower means for causing a fluid current to flow inwardly above said receiving means and rise in said chamber, revolving lifting up-tosser means opposite said receiving means and for lifting such material therefrom into the path of such inward current to subject fine material to its floating action, and deflector means above said revolving means for intercepting coarse material and deflecting it across such current.

7. In a separator, in combination, means affording a chamber, supply means for supplying pulverulent material to said chamber, shelf means below said chamber for receiving and sustaining such material, revolving up-tossers above said receiving means and for tossing such material upwardly therefrom, means below said chamber and above said receiving means affording a current passage, blower means for causing a fluid current to flow through such material to float fine material upwardly into said chamber, deflector means above said revolving means for intercepting and deflecting outward coarse material raised thereby, and receiver means outwardly of said deflecting means for receiving coarse material deflected therefrom.

60. 8. In a separator, in combination, means affording a separating chamber having a lower material out-dropping opening and having a lower current inlet and an upward current passage and an upper current outlet, means for supplying material to be separated

in said chamber, means for causing a fluid current to enter said chamber through said lower inlet and flow up through said upward passage and through said upper outlet for floating fine material from said chamber, and shelf means affording a material retaining sustaining wall below said lower material out-dropping opening for sustaining material to be separated adjacent to said inlet.

9. In a separator, in combination, means affording a separating chamber having a material out-dropping opening and having a lower current inlet and an upward current passage and an upper current outlet, means above said opening for supplying material to be separated in said chamber, means for causing a fluid current to enter said chamber through said lower inlet and flow up through said upward passage and through said upper outlet for floating fine material from said chamber, a receptacle for separated material below said opening, and shelf means comprising a material retaining sustaining wall below said material dropping opening and within said receptacle for sustaining material to be separated between said opening and said receptacle.

10. In a separator, in combination, means affording a separating chamber and having a lower current inlet and an upward current passage and an upper current outlet, means for supplying material to be separated in said chamber, means for causing a fluid current to enter said chamber through said lower inlet and flow up through said upward passage and through said upper outlet for floating fine material from said chamber, a receptacle below said chamber for receiving separated material, and shelf means comprising a material sustaining wall for sustaining material to be separated in the path of such current and disposed below said chamber and inwardly of said receptacle.

11. In a separator, in combination, means affording a separating chamber and having a lower current inlet and an upward current passage and an upper current outlet, means for supplying material to be separated in said chamber, means for causing a fluid current to enter said chamber through said lower inlet and flow up through said upward passage and through said upper outlet for floating fine material from said chamber, a receptacle for receiving separated material below said lower inlet and shelf means comprising a material sustaining wall for sustaining material to be separated inwardly of said receptacle and below said lower inlet.

12. In a separator, in combination, an outer casing enclosing an outer chamber, an upper receptacle in said casing and enclosing a separating chamber having a lower material dropping opening, and having upper and lower openings communicating with said outer chamber, a lower receptacle for receiv-

- ing separated material and spaced from said upper receptacle and having an upper end communicating with said outer chamber, means above said material dropping opening 5 for supplying material to be separated to said upper receptacle, means for causing a fluid current to flow up through said upper receptacle and upper opening into said outer chamber and return through said lower opening 10 for floating fine material from said separating chamber, and shelf means comprising a material retaining sustaining means spaced below said chamber and below said material dropping opening and between said receptacles 15 for sustaining between said receptacles material to be separated.
13. In a separator, in combination, means affording a separating chamber having a lower material out-dropping opening, and having a lower current inlet and an upper current outlet communicating with said chamber, means above said opening for supplying material to be separated to said chamber, means for causing a fluid current to enter said chamber through said inlet and flow up through said chamber and out through said outlet for floating fine material from said chamber, and material tossers below said material dropping opening and in the path of such material dropping through said opening for tossing such material into the path of such current.
14. In a separator, in combination, means affording a separating chamber and having a lower inward current inlet and an upper current outlet communicating with said chamber, means for supplying material to be separated to said chamber, means for causing a fluid current to enter said chamber horizontally inwardly through said lower inlet and flow upwardly through said chamber and out through said outlet for floating fine material from said chamber, and material tossers opposite said inlet for tossing such material into the path of such horizontally inwardly entering current.
15. In a separator, in combination, means affording a separating chamber having a lower material dropping opening, and having a lower current inlet and an upper current outlet communicating with said chamber, means above said opening for supplying material to be separated to said chamber, means for causing a fluid current to enter said chamber through said inlet and flow up through said chamber and out through said outlet for floating fine material from said chamber, and material uptossers below said material dropping opening and in the path of such material dropping through said opening and adjacent said inlet for tossing such material into the path of such current.
16. In a separator, in combination, means affording a chamber having a lower current inlet and an upper current outlet communi-
- cating with said chamber, means for supplying material to be separated to said chamber, means for causing a fluid current to enter said inlet and flow up through said chamber and out through said outlet for floating fine material from said chamber, material deflecting means adjacent to the path of such current for deflecting through such current coarse particles floating in such current, and material tossers opposite said deflecting means for tossing such material into the path of such current and toward said deflecting means. 70
17. In a separator, in combination, means affording a separating chamber having a lower material dropping opening, and having a lower current inlet and an upper current outlet communicating with said chamber, means for supplying material to be separated to said chamber, means for causing a fluid current to enter said chamber through said inlet and flow up through said chamber and out through said outlet to float fine material from said chamber, material retaining sustaining shelf means below said material dropping opening and for sustaining such material in the path of such current, and material dischargers for discharging such material from said sustaining means. 80
18. In a separator, in combination, means affording a separating chamber material dropping opening and having a lower current inlet and an upper current outlet communicating with said chamber, means above said opening for supplying material to be separated to said chamber, means for causing a fluid current to enter said chamber through said inlet and flow up through said chamber and out through said outlet for floating fine material from said chamber, material retaining sustaining shelf means below said opening for receiving such material dropping through said opening and for sustaining such material adjacent to the path of such current, and material tossers above said sustaining means and for tossing such material from said sustaining means. 90
19. In a separator, in combination, a casing enclosing a separating chamber having a lower material dropping opening and having a lower current inlet and an upper current outlet communicating with said chamber, means for supplying material to be separated to said chamber, means for causing a fluid current to enter said chamber through said inlet and flow up through said chamber and out through said outlet for floating fine material from said chamber, a receptacle for separated material below said opening, material retaining sustaining shelf means below said material dropping opening and above said receptacle for receiving such material dropping through said opening and sustaining such material adjacent to the path of such current, and material uptossing means. 110
- 120
- 125
- 130

above said sustaining means for tossing such material from said sustaining means.

20. In a separator, in combination, a casing enclosing a separating chamber and having a lower current inlet and an upper current outlet communicating with said chamber, means for supplying material to be separated to said chamber, means for causing a fluid current to enter said chamber through said inlet and flow up through said chamber and out through said outlet for floating fine material from said chamber, a receptacle for separated material below said supplying means, material sustaining shelf means below said supplying means and inwardly of said receptacle for sustaining such material adjacent to the path of such current, and material tosser means inward of said receptacle for tossing such material from said sustaining means into the path of such current.

21. In a separator, in combination, a casing enclosing a separating chamber and having a lower current inlet and an upper current outlet communicating with said chamber, means for supplying material to be separated to said chamber, means affording a return current passage communicating between said outlet and said inlet and affording an endless passage through and around said chamber, means for causing a fluid current to enter said chamber through said inlet and flow up through said chamber and through said outlet and return through said current passage for floating fine material from said chamber, material sustaining shelf means below and affording a lower wall for said lower inlet and below said supplying means and affording a lower wall for said chamber and for receiving and sustaining such material in the path of such returning current, and tosser means above said wall and around said inlet for tossing such material into the path of such returning current.

22. In a separator, in combination, a casing enclosing a separating chamber and having a lower current inlet and an upper current outlet, supply means for supplying material to be separated to said chamber, blower means for causing a fluid current to enter said chamber through said inlet and flow up through said chamber and through said outlet to float fine material from said chamber, and means within said chamber comprising a transverse cross chamber wall extending a substantial distance across said chamber and spaced below and adjacent to said outlet and spaced a substantial distance above said supplying means and affording below said wall and above said supplying means a substantial selection chamber in which large particles floating in such current toward said outlet may precipitate, and affording around the edge of said wall a passage for such current through which such current may flow from said selection chamber to said outlet.

23. In a separator, in combination, a casing enclosing a separating chamber and having a lower current inlet and an upper current outlet, supply means for supplying material to be separated to said chamber, blower means for causing a fluid current to enter said chamber through said inlet and flow up through said chamber and through said outlet to float fine material from said chamber, valve means above said chamber for varying the space through which such current is permitted to flow from said chamber, and wall means below said valve means and within said chamber comprising a transverse cross chamber wall extending a substantial distance across said chamber and spaced below and adjacent to said outlet and spaced a substantial distance above said supplying means and affording below said wall and above said supplying means a substantial selection chamber in which large particles floating in such current toward said outlet may precipitate and affording around the edge of said wall a passage for such current through which such current may flow from said selection chamber to said outlet, said valve means adjustable for varying the outflow of such current from said selection chamber for varying the fineness of material separated therein.

24. In a separator, in combination, a casing enclosing a separating chamber and having a lower current inlet and an upper current outlet, blower means for supplying material to be separated to said chamber, blower means for causing a fluid current to enter said chamber through said inlet and flow up through said chamber and through said outlet to float fine material from said chamber, and rotary wall means within said chamber comprising a transverse cross chamber wall extending a substantial distance across said chamber and spaced below and adjacent to said outlet and spaced a substantial distance above said supplying means and affording below said wall and above said supplying means a substantial selection chamber in which large particles floating in such current toward said outlet may precipitate and affording around the edge of said wall a passage for such current through which such current may flow from said selection chamber to said outlet.

25. In a separator, in combination, a casing enclosing a separating chamber and having a lower current inlet and an upper current outlet, supply means for supplying material to be separated in said chamber, blower means for causing a fluid current to enter said chamber through said inlet and flow up through said chamber and through said outlet to float fine material from said chamber, and means within said chamber comprising a transverse cross chamber partition wall extending a substantial distance across said chamber and spaced below and adjacent to

5 said outlet and spaced a substantial distance above said supplying means and affording below said wall and above said supplying means a substantial selection chamber in
6 which large particles floating in such current toward said outlet may precipitate and affording around the edge of said wall a passage for such current through which such current may flow from said chamber to said
10 outlet, said wall and said supply means the one vertically adjustable relatively to the other for varying the vertical distance between said wall and said supplying means for varying the fineness of material separated
15 in said substantial chamber.

26. In a separator, in combination, a casting enclosing a separating chamber and having a lower current inlet and an upper current outlet, supply means for supplying material to be separated in said chamber, blower means for causing a fluid current to enter said chamber through said inlet and flow up through said chamber and through said outlet to float fine material from said chamber,
20 valve means for varying the space through which such current is permitted to flow, and wall means below said valve means and within said chamber comprising a transverse cross chamber wall extending a substantial distance across said chamber and spaced below and adjacent to said outlet and spaced a substantial distance above said supplying means and affording below said wall and above said supplying means a substantial
25 selection chamber in which large particles floating in such current toward said outlet may precipitate and affording below said valve means and above said wall a passage for such current through which such current may flow from said selection chamber to said outlet.

27. In a separator, in combination, a casting enclosing a separating chamber and having a lower current inlet and an upper current outlet, supply means for supplying material to be separated in said chamber, blower means for causing a fluid current to enter said chamber through said inlet and flow up through said chamber and through said outlet to float fine material from said chamber, rotary valve means for varying the space through which such current is permitted to flow, and wall means below said valve means and within said chamber comprising a transverse cross chamber wall extending a substantial distance across said chamber and spaced below and adjacent to said outlet and spaced a substantial distance above said supplying means and affording below said wall and above said supplying means a substantial selection chamber in which large particles floating in such current toward said outlet may precipitate and affording around the edge of said wall a passage for such current through which such current may flow from said selection chamber to said outlet.

rent may flow from said selection chamber to said outlet.

28. In a separator, in combination, a casting enclosing a separating chamber and having a lower current inlet and an upper current outlet, supply means for supplying material to be separated in said chamber, blower means for causing a fluid current to enter said chamber through said inlet and flow up through said chamber and through said outlet to float fine material from said chamber, valve means for varying the space through which such current is permitted to flow, and rotary wall means below said valve means and within said chamber comprising a rotary transverse cross chamber wall extending a substantial distance across said chamber and spaced below and adjacent to said outlet and spaced a substantial distance above said supplying means and affording below said wall and above said supplying means a substantial selection chamber in which large particles floating in such current toward said outlet may precipitate and affording below said valve means and above said wall a passage for such current through which such current may flow from said selection chamber to said outlet.

29. In a separator, in combination, a casting enclosing a separating chamber and having a lower current inlet and an upper current outlet, supply means for supplying material to be separated in said chamber, blower means for causing a fluid current to enter said chamber through said inlet and flow up through said chamber and through said outlet to float fine material from said chamber, and adjustable wall means within said chamber comprising an adjustable transverse cross chamber wall extending a substantial distance across said chamber and spaced below and adjacent to said outlet and spaced a substantial distance above said supplying means and affording below said wall and above said supplying means a substantial selection chamber in which large particles floating in such current toward said outlet may precipitate and affording around the edge of said wall a passage for such current through which such current may flow from said selection chamber to said outlet.

30. In a separator, in combination, a casting enclosing a separating chamber and having a lower current inlet and an upper current outlet, supply means for supplying material to be separated in said chamber, blower means for causing a fluid current to enter said chamber through said inlet and flow up through said chamber and through said outlet to float fine material from said chamber, valve means for varying the space through which such current is permitted to flow, and adjustable wall means below said valve means and within said chamber comprising an adjustable transverse cross chamber wall ex-

tending a substantial distance across said chamber and spaced below and adjacent to said outlet and spaced a substantial distance above said supplying means and affording below said wall and above said supplying means a substantial selection chamber in which large particles floating in such current toward said outlet may precipitate and affording below said valve means and above 10 said wall a passage for such current through which such current may flow from said selection chamber to said outlet.

31. In a separator, in combination, a casing enclosing a separating chamber and having 15 a lower current inlet and an upper current outlet, supply means for supplying material to be separated to said chamber, blower means for causing a fluid current to enter said chamber through said inlet and flow up through 20 said chamber and through said outlet to float fine material from said chamber, valve means for varying the space through which such current is permitted to flow, and vertically adjustable wall means below said valve means 25 and within said chamber comprising a vertically adjustable transverse cross chamber wall extending a substantial distance across said chamber and spaced below and adjacent to said outlet and spaced a substantial distance 30 above said supplying means and affording below said wall and above said supplying means a substantial adjustable selection chamber in which large particles floating in such current toward said outlet may precipitate, and affording below said valve means 35 and above said wall a passage for such current from said selection chamber to said outlet and vertically adjustable to vary the space through which such current is permitted 40 to flow, for varying the fineness of material separated in said substantial chamber.

32. In a separator, in combination, means affording a separating chamber having a lower material dropping opening and having 45 a lower current inlet and an upward current passage and an upper current outlet, supply means above said opening for supplying material to be separated in said chamber, blower means for causing a fluid current to enter 50 said chamber through said inlet and flow up through said upward passage and through said upper outlet for floating fine material from said chamber, means communicating between said outlet and said inlet affording a 55 return passage for such current, filter means in said return passage for cleaning from such returning current fine material floating in such current, and shelf means comprising a material retaining sustaining wall below 60 said dropping opening for receiving material to be separated dropping through such opening and sustaining such material adjacent the path of such cleaned returning current entering through said inlet.

33. In a separator, in combination, means

affording a separating chamber having a lower material dropping opening and having a lower current inlet and an upward current passage and an upper current outlet, supply means above said opening for supplying material to be separated in said chamber, blower means for causing a fluid current to enter said chamber through said inlet and flow up through said upward passage and through said upper outlet for floating fine material from said chamber, means communicating between said outlet and said inlet affording a return passage for such current, filter means in said return passage for cleaning from such returning current fine material floating in such current, and shelf means affording a material retaining sustaining wall below said dropping opening and below said cleaning means. 70

34. In a separator, in combination, means affording a separating chamber having a lower material dropping opening and having a lower current inlet and an upward current passage and an upper current outlet, supply means above said opening for supplying material to be separated in said chamber, blower means for causing a fluid current to enter said chamber through said inlet and flow up through said upward passage and through said upper outlet for floating fine material from said chamber, means communicating between said outlet and said inlet affording a return passage for such current, filter means across said return passage for cleaning from such returning current fine material floating in such current, and shelf means affording a material retaining sustaining wall below said dropping opening and below said inlet for receiving material to be separated dropping through said opening and sustaining such material in the path of such cleaned current returning to said inlet. 80

35. In a separator, in combination, means affording a separating chamber having a lower material dropping opening and having a lower current inlet and an upward current passage and an upper current outlet, supply means above said opening for supplying material to be separated in said chamber, blower means for causing a fluid current to enter said chamber through said inlet and flow up through said upward passage and through said upper outlet for floating fine material from said chamber, means communicating between said outlet and said inlet affording a return passage for such current, filter means around said return passage for cleaning from such returning current fine material floating in such current, and shelf means affording a material retaining sustaining wall below said dropping opening and spaced below said

chamber for receiving material to be separated dropping through said opening and sustaining such material below said chamber and adjacent the path of such cleaned returning current.

36. In a separator, in combination, means affording a separating chamber having a lower material dropping opening and having a lower current inlet and an upward current passage and an upper current outlet, supply means above said opening for supplying material to be separated in said chamber, blower means for causing a fluid current to enter said chamber through said inlet and flow up through said upward passage and through said upper outlet for floating fine material from said chamber, means communicating between said outlet and said inlet affording a return passage for such current, filter means across said return passage for cleaning from such returning current fine material floating in such current, and shelf means affording a material retaining sustaining wall below said dropping opening and below said return current passage for receiving material to be separated dropping through said opening and sustaining such material below the path of such cleaned returning current.

37. In a separator, in combination, means affording a separating chamber having a lower material dropping opening and having a lower current inlet and an upward current passage and an upper current outlet, supply means above said opening for supplying material to be separated in said chamber, blower means for causing a fluid current to enter said chamber through said inlet and flow up through said upward passage and through said upper outlet for floating fine material from said chamber, means communicating between said outlet and said inlet affording a return passage for such current, filter means in said return passage for cleaning from such returning current fine material floating in such current, and shelf means affording a material retaining sustaining wall below said supplying means for receiving material to be separated falling from such supplying means and sustaining such material adjacent the path of such cleaned returning current and spaced at its outer edge from the wall of said chamber and affording around its outer edge and between it and such wall an annular passage for such cleaned current returning from said cleaning means to said chamber.

38. In a separator, in combination, means affording a separating chamber having a material dropping opening and having a lower current inlet and an upward current passage and an upper current outlet, supply means for supplying material to be separated in said chamber, blower means for causing a fluid current to enter said chamber through said inlet and flow up through said upward passage and through said outlet for float-

ing fine material from said chamber, means surrounding said chamber affording a return passage for such current communicating from said outlet to said inlet, filter means around said chamber and in said return passage for cleaning from such current fine material floating in such current returning toward said inlet, and shelf means affording a material retaining sustaining wall below said dropping opening and inwardly of and surrounded by said cleaning means for receiving material to be separated dropping through said opening and sustaining such material in the path of such cleaned returning current inwardly of said cleaning means.

39. In a separator, in combination, means affording a separating chamber having a material dropping opening and having a lower current inlet and an upper current outlet, supply means for supplying material to be separated in said chamber, blower means for causing a fluid current to enter said chamber through said inlet and flow up through said outlet for floating fine material from said chamber, means affording a return current passage communicating between said outlet and said inlet for returning such current to said inlet, filter means around said inlet for cleaning from such current fine material floating in such current to said inlet, and shelf means affording a material retaining sustaining wall below said opening and below said inlet for receiving material to be separated dropping through said opening, and sustaining such material below said inlet and adjacent the path of such cleaned current returning from said cleaning means.

40. In a separator, in combination, a casing enclosing a separating chamber having a material dropping opening and having a lower current inlet and an upper current outlet, supply means for supplying material to be separated in said chamber, blower means for causing a fluid current to enter said chamber through said inlet and flow up through said outlet for floating fine material from said chamber, means affording a return current passage communicating between said outlet and said inlet for returning such current, filter means in said passage for cleaning from such current fine material floating in such current to said inlet, and material uptosser means below said dropping opening and in the path of material to be separated dropping through such opening for uptossering such material in the path of such cleaned current returning from said cleaning means.

41. In a separator, in combination, means affording a separating chamber having a material dropping opening and having a lower current inlet and an upper current outlet, supply means for supplying material to be separated in said chamber, blower means for causing a fluid current to enter said chamber

through said inlet and flow up through said outlet for floating fine material from said chamber, means affording a return current passage communicating between said outlet and said inlet for returning such current to said inlet, filter means in said return passage for cleaning from such current fine material floating in such current to said inlet, and material tosser means below said opening and below said cleaning means and in the path of material to be separated dropping through said opening for tossing such material into the path of such cleaned current returning through said cleansing means.

42. In a separator, in combination, means affording a separating chamber and having a lower current inlet and an upper current outlet, supply means for supplying material to be separated in said chamber, blower means for causing a fluid current to enter said chamber through said inlet and flow up through said outlet for floating fine material from said chamber, means affording a return current passage communicating between said outlet and said inlet for returning such current to said inlet, filter means in said passage and around said inlet for cleaning from such current fine material floating in such current to said inlet, and material tosser means below said dropping opening and concentric of said cleaning means for receiving material to be separated dropping through said opening and tossing such material concentrically of said cleaning means into the path of such cleaned returning current.

In witness whereof, I have hereunto signed my name.

40 GEORGE HOLT FRASER.
